MAGNETIC CYLINDER LOCKS

Enrique Jorge Hall, Roque Saenz Pena 788,
Buenos Aires, Argentina

Filed Dec. 19, 1958, Ser. No. 781,676

3 Claims. (Cl. 70—276)

The present invention refers to improvements in magnetic cylinder locks and more particularly to magnetic locks having a fixed outer cylinder containing a rotatory barrel connected to the corresponding latch or bolt and blocking means to prevent the rotation of said barrel within said cylinder.

According to the instant invention said blocking means consist of a plurality of permanent magnets in the form of tumbler pins or bolts insertable between said barrel and said cylinder and displaceable by the action of an equal number of other permanent magnets fixed in the shank of the corresponding key, by the use of which said barrel is allowed to rotate freely.

One of the principal improvements afforded by the instant invention is the provision of an increase in the number of possible combinations and this is achieved by the special arrangement according to which the magnetic tumbler pins in the outer cylinder are disposed in lines along at least two generatrices of said cylinder, thereby allowing the use of an increased number of pins without the danger of interference between same.

Another important object of the novel type of lock is achieved by disposing the permanent magnets corresponding to the key in such manner that those fixed in one edge of same are alternately positioned or staggered in respect to those of the opposite edge of said key, said arrangement also permitting an increase in the number of said magnets with the aforesaid advantages.

This invention is further characterized by the provision of at least one longitudinal recess in the surface of the interior barrel, said recess being of a predetermined size and shape so as to co-operate with the said magnetic tumbler pins in causing a stop or arrest of the rotation of said barrel in one of its intermediate positions, thereby providing this type of lock with appreciably improved conditions of security.

Additional objects of the instant invention will become evident in the course of this specification.

To facilitate a clear understanding and easy practical production of the instant invention, a preferred embodiment of same is illustrated in the accompanying drawings, wherein:

Fig. 1 shows a longitudinal mid-section through the lock taken on the line A—A of Fig. 2, with the magnetic tumbler pins in locking position;

Fig. 2 shows a cross-section of the same lock taken on the line B—B of Fig. 1;

Fig. 3 shows a cross-section similar to that shown in Fig. 2, with the barrel locked in an intermediate position;

Fig. 4 shows a similar cross-section with the barrel in unlocked position and free to rotate;

Fig. 5 is a perspective view of the separate elements of the lock and key constituting the embodiment in accordance with the instant invention.

In the embodiment illustrated the novel type of lock according to the instant invention comprises an exterior

hollow cylinder 1 inside of which is mounted the corresponding barrel 2 fitted for rotation within the cylinder. The barrel has an axial central recess 3 therein for reception of a key 4, and is integral at one end with a rod 5 for connection with the corresponding latch or bolt (not shown).

According to the instant invention the cylinder 1 carries a plurality of permanent magnets 6a and 6b in the form of tumbler pins or bolts, freely slideable in a corresponding number of orifices 7, drilled through the wall of said cylinder 1 and closed at their outer ends by grub screws or the like 8.

The said magnets 6a and 6b are disposed in the upper portion of the cylinder 1 in line along two generatrices 15 (a) and (b) at a convenient distance apart in order to avoid any attraction or repulsion between the magnets of the separate lines, whereby the number of said magnets can be increased considerably while separating same sufficiently to prevent any possible interference between them.

In the embodiment of the lock that is illustrated, merely as an example but without being limited in any way, the device is provided with thirty-five magnets, disposed in three rows, but it should be noted that this number 25 can be increased or decreased according to the requisite conditions of each case, whereby the number of combinations obtainable is greatly increased.

The rotatable barrel 2 in turn, is provided with a plurality of radial openings 9, arranged to hold an equivalent number of permanent magnets 10, disposed along one lower spring line, but in substantially opposite position to the lines of the upper magnets 6a and 6b, as shown in Fig. 1, and adapted to bolt or lock at their lower ends by engaging a longitudinal recess or slot 11 formed in the lower internal portion of the fixed cylinder 1.

In Figs. 2 and 4 it can be seen that the rotatable barrel 2 is also provided with a longitudinal recess or slot 12 which is of a width slightly greater than the angular 40 distance separating the projecting ends of the upper rows of magnets 6a and 6b and adapted so as to receive the ends of said rows of magnets when in locked position.

This type of lock is operated by means of a special key 4, comprising a substantially rectangular shank, the 45 opposite, narrower smooth edges whereof are provided with separated series of magnets 13 and 14, disposed alternately or staggered and adapted to coincide in position with the respective magnetic tumbler pins 6a and 6b and 10 upon complete insertion of said key into the 50 opening 3 of the barrel 2.

Each of the said magnets in row 13 of the key 4 is so arranged that its polarity is identical with that of the corresponding tumbler pin in the rows 6a and 6b in coaxial alignment when the key is inserted in the lock 55 and each of the magnets in row 14 of the key is arranged so that, when the key is in the lock, the polarity of each magnet is opposite to that of the corresponding magnet in row 10 of the barrel.

When in locked position, the barrel 2 is disposed in the 60 cylinder 1 as shown in Figs. 1 and 2. Upon withdrawal of the key 4 from the lock, the upper magnets 6a and 6b drop by their own weight and enter the upper recess 12 in the barrel, while the lower magnets 10 also drop by their own weight from their former positions in the 65 barrel and engage the recess 11, cut in the inner surface of the cylinder 1 and thereby completely immobilize said barrel. Thus, the tumbler pins in the row 6a, by their contact with the barrel 2 in the upper recess 12, lock the barrel against rotation in one direction; and the tumbler pins in the row 6b, by their contact with the barrel 2 in the upper recess 12, also lock the barrel 70

against rotation in one direction. The lower tumbler pins 10, by their contacts with the recess 11, lock the barrel against rotation in both directions.

Upon complete insertion of the key 4 as shown by broken lines in Fig. 1, and in consequence of the identical polarity of the magnets 13 and 6a in coaxial alignment, the latter row 6a of magnets or tumbler pins will be repelled upwardly, thereby unblocking the recess 12, while the opposite polarity between the magnets and tumbler pins 10 will cause the latter to be attracted and consequently raise the latter row of magnets or tumbler pins 10 into their respective openings within the body of the barrel 2, thereby freeing the recess 11 and allowing the barrel to be rotated by the key 4 in the direction shown by the arrow in Fig. 3.

This rotation of the barrel is stopped at an intermediate position indicated in Fig. 3, due to the edge 12a of the recess 12 coming into contact with the edge of magnets or tumbler pins, which latter are in turn repelled and moved into their respective openings 7 in the outer cylinder 1 when confronted by the corresponding magnets 13 of the key 4, thereby releasing the edge 12a of the recess 12 and allowing the barrel 2 to be turned until the lock is completely open.

Upon giving a reverse turn to the barrel 2 in order to return same to its original position as shown in Fig. 2, and withdrawal of the key 4 the repellent action between the magnets in the rows 6a and 6b having ceased, said magnets fall by gravity into the recess 12 while the lower row of magnets 10, freed from the magnetic attraction of those in the key 4 fall, in turn, into the slot 11 of the external cylinder 1 thereby locking the barrel 2 and preventing any rotation of same. The operation of this type of lock is furthermore facilitated by the provision of checking or retaining means, consisting of a ball 15 and spring 18 lodged in an opening 16 drilled in the external cylinder 1 and regulated by means of a grub screw 19, said ball 15 being adapted to enter the shallow cavities 17a and 17b provided on the surface of the barrel 2. These cavities 17a and 17b are arranged at the same distance from each other as the width of the longitudinal recess 12 in the barrel 2, so that the first cavity 17a, in cooperation with the ball 15, holds the barrel 2 at the moment in which the magnets 13 of the key 4 confront the corresponding magnets 6a and 10 in the key and the barrel, respectively, as illustrated in Fig. 2, and the cavity 17b in turn, will co-operate with the ball 15 and will hold the barrel 2 when in the position shown in Fig. 3.

From the foregoing description it will have become clear that the number of different combinations can be increased to an unlimited extent by altering the number of magnetic tumbler pins 6a, 6b and 10 and the co-operating magnets 13 and 14 of the corresponding key 4, as well as by inverting the polarity of one or more of same. This can also be done by the addition of one or more rows of magnets, disposed in angular relationship upon the outer and inner spring lines of the cylinder 1.

This invention has now been clearly described and explained in a manner that will be readily understood by those skilled in the art. It will be obvious, however, that the invention is susceptible of various changes and modifications without departing from the spirit or scope of the invention or sacrificing any of the advantages and I accordingly claim all such forms of the device to which I am entitled by the appended claims.

What is claimed is:

1. A magnetically controlled cylinder lock comprising a hollow cylinder having a plurality of radial orifices

in the upper portion thereof formed in axial alignment along at least two generatrices of said cylinder, the radial orifices formed along the generatrices being similarly spaced therealong, said cylinder also having an inner longitudinal recess in the lower portion thereof; a barrel fitted for rotation within said cylinder having an axial central recess therein for reception of a key, having a radial opening in the lower portion thereof registerable with the inner longitudinal recess in the lower portion of said cylinder, and having a longitudinal recess in the upper portion thereof of a width slightly greater than the angular distance between the outermost lines of radial orifices in said cylinder; a permanently magnetic tumbler pin longitudinally movable in each of the radial orifices in said cylinder; and a permanently magnetic tumbler pin longitudinally movable in the radial opening in said barrel and engageable with the longitudinal recess in said cylinder; whereby said tumbler pins in the radial orifices of said cylinder move by gravity into engagement with the longitudinal recess in said barrel to lock the latter against turning in either direction in said cylinder and said tumbler pin in the radial opening in said barrel moves by gravity into engagement with the radial opening in the lower portion of said cylinder, and whereby magnetic action may displace said tumbler pins from such respective engagements to permit rotation of said barrel in said cylinder.

2. A magnetically controlled lock according to claim 1 wherein the axes of the radial orifices in axial alignment along one generatrix of said cylinder are parallel to that of the axis of the radial opening in said barrel when said barrel is in locked position, whereby said tumbler pins in the radial orifices having axes parallel to the axis of the radial opening in said barrel lock said barrel against rotation in one direction and the tumbler pin in the radial opening in said barrel locks said barrel against rotation in both directions.

3. A magnetically controlled lock according to claim 1 wherein said barrel has a plurality of radial openings in the lower portion thereof aligned to register with the inner longitudinal recess in the lower portion of said hollow cylinder, the axes of such radial openings being coplanar with the axes of the plurality of radial orifices formed along one of the generatrices of said cylinder and spaced axially between the axes of such radial openings, in combination with a key insertable into the axial central recess in said barrel, magnets positioned along one edge of said key to register with the tumbler pins in the radial orifices formed along each generatrix of said cylinder and having a polarity like the pin with which it registers, and magnets positioned along the opposite edge of said key to register with the tumbler pins in the radial openings in the lower portion of said barrel and having a polarity opposite to that of said tumbler pins in the lower portion of said barrel, whereby said key when inserted into the axial central recess in said barrel repels the tumbler pins in the radial orifices in said cylinder back into such orifices and out of engagement with the longitudinal recess in said barrel and attracts the tumbler pins in the radial openings in said barrel back into such openings and out of engagement with the longitudinal recess in said cylinder to permit rotation of said barrel in said cylinder by said key and opening of the lock.
